UNITED STATES PATENT OFFICE.

NEVIL MONROE HOPKINS, OF WASHINGTON, DISTRICT OF COLUMBIA.

APPARATUS FOR PREVENTING BURSTING OF WATER-PIPES BY FREEZING.

SPECIFICATION forming part of Letters Patent No. 626,908, dated June 13, 1899.

Application filed March 16, 1899. Serial No. 709,332. (No model.)

To all whom it may concern:

Be it known that I, NEVIL MONROE HOPKINS, a citizen of the United States, residing in the city of Washington, District of Columbia, have invented certain new and useful Improvements in Apparatus for Preventing the Bursting of Water-Pipes by Freezing, of which the following is a specification.

In my Patent No. 616,188, of December 20, 1898, I have shown a series of expansion-chambers applied to a water-pipe and so arranged that the freezing water or ice expands into the chambers without causing the pipe itself to expand or burst. The expansion-chambers are filled with air and are air-tight, the water normally being for the most part excluded from the chambers by the air, which is compressed by the water if it tends to enter too far into the chambers. I have found, however, that when the flow of water is constant, long continued, and rapid the air in the chambers is partially if not wholly withdrawn owing to the aspirating effect of flowing water. This reduction in volume of the air causes the water to rise and partially fill the expansion-chambers, so as to leave insufficient space for the expanding water or ice. According to my present invention I provide means for supplying an additional quantity of air to the chambers, so that they may always be filled to such an extent as to exclude water therefrom under ordinary conditions, but which is compressed to make room for freezing water and ice when required.

The accompanying drawing shows a water-pipe system with my improvements applied.

The main supply-pipe A is connected at a to a service-pipe B, that is furnished with faucets C at different points.

D indicates two of the improved expansion-chambers shown in my patent of December 20, 1898, above referred to, and E indicates a modified form of expansion-chamber also shown in my patent.

In a system such as thus far described there is liability of the water rising and filling the expansion-chambers, especially when the flow is constant, long continued, and rapid. To overcome this objection, I provide means for supplying an additional quantity of air to the chambers. There are several ways in which this may be accomplished. At F, I

have shown by dotted lines a pump for forcing air into the main supply-pipe A. This pump may be located at any point in the main, either at the pumping-station or remote therefrom, or it may be applied to the service-pipes of a building. Air forced into the pipe by the pump will travel with the water toward the expansion-chambers and will float upward and rise into them and become compressed therein, and thus exclude the water. The preferred means for supplying air to the chambers is, however, shown at G, which is a contrivance adapted to automatically admit air when water is flowing in the pipe. A vessel g is formed with an opening g', provided with an internal valve-seat fitting a valve g'', carried by a float g''. The casing is connected to the pipe B by a passage g², opened and closed by a cock g⁵. Lugs or rails g⁶, either on the float or on the bottom of the inside of the vessel, prevent the float from dropping too far, so as to close the passage g². Preferably the pipe B at this point is a separate section provided with a nozzle x, extending past the passage g² and into a sleeve x', flared at opposite ends. By this arrangement when the cock g⁵ is open and water is flowing in the pipe air will be drawn in past the valve g'', through the opening g², and into the service-pipe. It will pass along the pipe with the water and will rise in the expansion-chambers. By thus supplying the chambers with an additional amount of air I have completely overcome the difficulties experienced in some cases with the use of the invention covered by my patent before referred to.

The drawing merely illustrates one way of embodying my invention. The expansion-chambers should be located at such points as to meet the requirements of each case, and the devices for admitting or supplying air to the system may be varied in construction and location according to circumstances.

While I of course prefer to use air for the expansion-chambers, any other suitable gas may be substituted.

I do not herein claim the modified form of expansion-chamber shown at E in the accompanying drawing, as this subject-matter is claimed in my application for Patent, Serial No. 715,364, filed May 2, 1899.

I claim as my invention—

1. The combination of a water-pipe provided with an expansion-chamber to receive freezing water or ice, and devices for supplying a gas, such as air, to the chamber.
- 5 2. The combination of a water-pipe provided with an expansion-chamber to receive freezing water or ice, and a device connected with the water-pipe for supplying air to the water-pipe from which it in turn passes to the expansion-chamber.
- 10 3. The combination of a water-pipe provided with an expansion-chamber to receive freezing water or ice, and means for admitting or forcing air into the water-pipe.
- 15 4. The combination of a water-pipe provided with an expansion-chamber to receive freezing water or ice, an air-inlet port for admitting air to the water-pipe, a valve control-
ling this port, and a nozzle in the pipe extending past the port.
5. The combination of a water-pipe provided with an expansion-chamber to receive freezing water or ice, a vessel communicating with the water-pipe and having an air-inlet, a valve controlling the air-inlet, a float to 25 which the valve is attached, and a nozzle within the water-pipe extending past the passage between the water-pipe and the valve-chamber.
- In testimony whereof I have hereunto subscribed my name.

NEVIL MONROE HOPKINS.
